(57) **CLAIM**

The ornamental design for a fender panel of car, as shown and described.

DESCRIPTION

FIG. 1 is a perspective view of new design for the right fender panel of car as shown in the drawings (the left fender panel of car being a mirror image and is not shown);

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.
